(57) **CLAIM**

The ornamental design for a peripheral display for smartphone, as shown and described.

DESCRIPTION

FIG. 1 is a front view of a first embodiment of a peripheral display for smartphone, showing our new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a front, left perspective view thereof;

FIG. 8 is a rear, left perspective view thereof;

FIG. 9 is a front view thereof, shown in a rotation condition;

FIG. 10 is a right side view thereof, shown with the screen tilted;

FIG. 11 is a rear view thereof, shown with connector cable;

FIG. 12 is a rear view thereof, shown with connector cable and power cable;

FIG. 13 is a front view of a second embodiment of a peripheral display for smartphone, showing my new design;

FIG. 14 is a rear view thereof;

FIG. 15 is a left side view thereof;

FIG. 16 is a right side view thereof;

FIG. 17 is a top plan view thereof;

FIG. 18 is a bottom plan view thereof;

FIG. 19 is a front, left perspective view thereof;

FIG. 20 is a rear, left perspective view thereof;

FIG. 21 is a front view thereof, shown in a rotation condition;

FIG. 22 is a right side view thereof, shown with the screen tilted;

FIG. 23 is a rear view thereof, shown with connector cable; and,

FIG. 24 is a rear view thereof, shown with connector cable and power cable.

(Continued)

The broken lines shown in the drawings illustrate portions of the peripheral display for smartphone that form no part of the claimed design.
